UNITED STATES PATENT OFFICE.

ARTHUR ROBERTS, OF EVANSTON, ILLINOIS.

COKE-OVEN TAKE-OFF.

1,198,582.

Specification of Letters Patent. Patented Sept. 19, 1916.

Continuation of application Serial No. 22,145, filed April 17, 1915. This application filed August 4, 1916.
Serial No. 43,752.

To all whom it may concern:

Be it known that I, ARTHUR ROBERTS, a citizen of the United States, residing at Evanston, county of Cook, and State of Illinois, have invented certain new and useful Improvements in Coke-Oven Take-Offs, of which the following is a specification:

The present invention has reference to certain improvements in take-offs for coke ovens, whereby the distillate gases are received and removed from the carbonizing chamber.

The invention also has reference to the construction of the upper portion of the carbonizing chamber, and to the provision of means for subjecting the distillate gases to a preliminary treatment directly after they leave the carbonizing chamber, and in preparation for their subsequent treatment as in a by-product recovery apparatus.

One of the features of the invention has reference to the provision of a construction such that the gases may be withdrawn by a very short and direct path of travel from the upper portion of the carbonizing chamber, thereby preventing the gases from being subjected to the destructive action of the heat of the carbonizing chamber after they have been formed and are ready for delivery.

In this connection another object is to provide a take-off of such construction that the oven can be directly charged through the same ports through which the gases are withdrawn, but a construction such that during the charging operation coal dust and the like will not find its way into the take-off flues or passages. This will overcome a very serious objection to many present forms of take-off construction.

Other objects and uses will appear from a detailed description of the invention which consists in the features of construction and combinations of parts hereinafter described and claimed.

Referring to the drawings: Figure 1 shows a longitudinal section through an oven equipped with a take-off device embodying the features of the present invention; Fig. 2 shows a cross section taken on the line 2-2 of Fig. 1 looking in the direction of the arrows; Fig. 3 shows an enlarged horizontal section through a portion of the dome of Figs. 1 and 2; Fig. 4 shows a section taken on the line 4-4 of Fig. 3

looking in the direction of the arrows; Fig. 5 shows a horizontal section similar to that of Fig. 3 with the exception that it illustrates a modified form of dome; and Fig. 6 shows a section taken on the line 6-6 of Fig. 3 looking in the direction of the arrows.

In the several figures the carbonizing chamber of the coke oven is designated by the numeral 7. This carbonizing chamber 65 may be of any one of a number of suitable construction, the particular construction illustrated embodying the type of heating wall disclosed in Letters Patent of the United States, No. 1,372,685, issued to me 70 on March 23, 1916. For the above reasons I do not find it necessary to describe the particular construction of the coke oven in detail in this specification.

The roof 8 of the carbonizing chamber is 75 provided with a plurality of ports 9, there being ordinarily four or five of these ports, although any suitable number may be used. A desirable location for these ports is along 80 the center line of the roof, as shown in Figs. 2 and 3.

Each of the ports extends up through the roof and communicates directly with a tubular flange or the like 10, as best shown in Fig. 2. A convenient form of construction at this point includes a cast iron collar or the like 11 seated down into the upper surface of the roof, the flange being bolted or otherwise rigidly secured thereto.

The various flanges 10 support the take-off flue or dome 12 which extends lengthwise over the roof and carries the distillate gases toward the desired point of delivery. In the particular arrangement illustrated the dome 12 communicates with either of the mains 13 and 13' in which the gases from a batch of ovens are collected and carried to the by-product apparatus or other point of delivery. The dome is preferably made up from a series of sections 13 which are joined in register with the number of ports. Each of these sections has an enlarged longitudinally extending body portion 14, near the center of which is the downwardly extending throat 15 which seats onto and is secured to the corresponding flange 10. All of the enlarged body portions 14 align with each other and are connected up to provide a continuous enlarged flue or passage through which the

gases are taken off and is which may be subjected to preliminary treatment. Between each of the throats 14 is the projection 15, flange 16 which provides for the application of tension of the corresponding pipe 17. Liquid materials collecting in the bottom of the longitudinal passage 14 will be prevented from running down through the ports 18 and onto the ports by means of the projection 19 of the flanges 16. Above each of the ports 18 and flanges 16 is a cleaving sprout 20 which may be closed by a cover 21. Each sprout 20 is connected to a bell mouth 22 which is connected to a link 23 and having a connection 24 to a valve 25. The operation of this device is clearly shown in Fig. 4.

At one end the dome 12 is closed by a cover 22, and at its other end it communicates with a trap 23. The delivery pipe 24 which meets the upper portion of the pipe 20, both of the arms 14 and 15, and the gas may be directed into either of the ports by the valves 25 and 26.

The herein described dome and valve 26 construction are particularly well adapted for use in connection with a type of carburing apparatus in which a sleeve 27 is dropped down into each of the ports 18 and 19, and the powdered coal or coke contained in the sleeve 27 through the ports 18 and 19 is delivered into the carburing chamber 11. In Fig. 4 I have illustrated the sleeve 27 as being in position for a particular purpose. The opening 17 of the sleeve 27 may be easily accommodated between the ports 18 and 19. The sleeve 27 is dropped down its housing 28 and into engagement with the sleeve 16 of Fig. 16. In order to insure a tight connection between the sleeve 27 and the sleeve 16, it is to bare the upper edge of the sleeve 27 to the ports 18 and 19 and if desired the lower edge of the sleeve 27 may be slightly coned. It is also further to insure a tight connection when the sleeve 27 is lowered. With this arrangement as soon as the sleeve 27 is lowered into place the passage 14 is closed off and cut off from communication with the ports 18 and 19, thus preventing the raising of the sleeve 27, and at the same time the ports 18 and 19 will be cut off from communication with the ports 14. Consequently the coal and coke introduced through the sleeve 27 will not be forced find their way into the ports 18 and 19 and the passage will be kept clean and in good condition. In this manner, thereby preventing the deterioration of the ports and by-passes and eliminating a very facie problem of carburing troubles.

Along the sides of the pipe 20 there extend the pipes 28 and 29 which are intended for the delivery of an appropriate amount of preliminary treatment of the gas. These pipes 28 and 29 are connected to the pipe 20 in accordance with the direction of the arrows 30. My co-pending application for Letters Patent of the United States on improvements, Serial No.

22,146, executed by me April 14, 1915, and filed April 17, 1915, as Serial No. 22,147. Each of these pipes connects with a plurality of nozzles 30 which communicate just inside of the longitudinal passage 14, and the nozzles on the two sides of the pipe 20 and passages may be staggered with respect to each other as shown in Fig. 3. The valves 31 serve to control the delivery of spray through each nozzle. Both of the pipes 28 and 29 may receive their emulsion from a common source, or in any other manner desired. The passage 14 preferably inclines slightly toward the trap 23 so that any surplus oil or emulsion will drain toward said trap from which it may be withdrawn through the connection 32.

In the modified construction shown in Figs. 5 and 6, the passage 14 is located to one side of the ports, and the space between said ports is left free and unobstructed to a very much greater extent than is the case with the construction previously described. However, the principles of construction and operation of this modified construction are the same as those heretofore described.

As set forth more in detail in my co-pending application for Letters Patent of the United States on improvements in by-product recovery processes, Serial No. 22,147, executed April 14, 1915, and filed April 17, 1915, it is very desirable to be able to control or alter the temperature or composition, or both, of the distillate gases immediately after they are delivered from the carburing chamber, and preparatory to their subsequent treatment for the recovery of by-products. Such preliminary treatment for control of temperature and composition of the gases can be readily effected by the injection of a suitable oil or emulsion into the gases as they are delivered from the carburing chamber, said oil or emulsion being of proper temperature and composition and being injected in suitable quantities, to obtain the desired control. Of course, the temperature, quantity and composition of the oil or emulsion so injected will be determined in each case by the condition of the gas as delivered from the carburing chamber, and by the condition into which it may be desired to modify the gas, but in any case the features of invention disclosed herein may be used for securing the desired control.

This application is a continuation of an application for Letters Patent of the United States on improvements in coke oven take-offs, Serial No. 22,144, executed by me April 14, 1915, and filed April 17, 1915.

While I have herein shown and described only certain forms of construction, still it will be understood that I am not limited to the same, except as I may limit myself in the claims.

I claim:

1. A gas take-off for a coke oven, said take-off comprising a plurality of ports extending upwardly through the roof of the carbonizing chamber of the oven, a longitudinally extending dome of substantially uniform cross section, a connection from each port into the lower side of the dome, a circular flange within the dome and extending upwardly around each of said connections, there being charging openings along the upper portion of the dome in vertical alignment with said flanges, covers for said openings, spray nozzles extending into the side portions of the dome throughout substantially its entire length, pipes for delivering emulsion or the like to said nozzles, and a trap for the collection of excess emulsion delivered through the nozzles.
2. In a take-off for coke ovens the combination of a plurality of ports extending upwardly through the roof of the carbonizing chamber of the oven, a longitudinally extending dome above said ports, a connection from each port upwardly into the lower portion of the dome, a circular flange surrounding the upper end of each of said connections, a charging opening in the upper portion of the dome above each flange and of substantially the same diameter as the flange, and a cover for each of said openings.
3. In a take-off for a coke oven the combination of a plurality of ports extending upwardly through the roof of the carbonizing chamber of the oven, a longitudinally extending dome above said ports, a connection from each port to the lower portion of the dome, a flange surrounding each of said connections and upstanding into the body of the dome, a charging opening above each port and of size and contour substantially the same as that of the flange of the said port, and a cover for each of said openings.
4. In a take-off for a coke oven the combination of a plurality of ports extending upwardly through the roof of the carbonizing chamber, a longitudinally extending dome above said ports, a connection from each port into the lower portion of the dome, a flange extending upwardly around each of said connections and into the body of the dome, a charging opening above each port, and a cover for each charging opening.
5. In a take-off for a coke oven the combination of a plurality of ports extending upwardly through the roof of the coke oven, a longitudinally extending dome of substantially rectangular cross section above said ports, a connection from each port into the bottom side of said dome, a flange extending upwardly around each of said connections and into the body of the dome, a charging opening above each of said connections, and a cover for each charging opening.
6. The combination with the carbonizing chamber of a coke oven, of a gas collecting main extending along above the carbonizing chamber, gas delivery connections from the carbonizing chamber into the lower portion of the main at various points throughout its length for the purpose of delivering freshly distilled gas into the main, means for injecting emulsion or the like into the body of gas within the main, and means for preventing a flow of excess portions of said emulsion down through the gas connections into the carbonizing chamber.
7. The combination with the carbonizing chamber of a coke oven, of a gas collecting main mounted above the carbonizing chamber, a plurality of gas connections from the carbonizing chamber to the main for the purpose of delivering freshly distilled gas from the carbonizing chamber to the main, and means for delivering emulsion or the like into the gas flowing through the main.
8. The combination with a gasifying chamber, of a gas collecting main extending throughout the major portion of the length of said chamber, a plurality of gas delivery connections from said chamber to said main, said connections being located at various points throughout the major portion of the length of the chamber, for the purpose of delivering freshly generated gas uniformly from the chamber to the main, and means for delivering emulsion or the like into the body of the gas flowing through the main, at various points throughout the length of the main.
9. The combination with a gasifying chamber, of a gas collecting main extending throughout the major portion of the length of said chamber, a plurality of gas delivery connections from the chamber to said main, said connections being located at various points throughout the major portion of the length of the chamber, for the purpose of delivering freshly generated gas uniformly from the chamber to the main, and means for delivering emulsion or the like into the body of the gas flowing through the main.
10. The combination with a gasifying chamber, of means for collecting freshly generated gas from various points throughout the length of said chamber, and means for subjecting said gas, adjacent to each point of collection, to treatment by an emulsion or the like.
11. The combination with a gasifying chamber, of means for collecting freshly generated gas from various points throughout the length of said chamber and for delivering said gas into a common pipe, and means for subjecting gas so collected to treatment by an emulsion or the like immediately after the collection of the gas.
12. The combination with a gasifying chamber, of means for collecting freshly

generated gas therefrom, and means for subjecting the gas so collected to suitable treatment after collection, for the purpose of controlling the condition of saturation and 5 temperature of the gas.

13. The combination with a gasifying chamber, of a gas collecting header, a plurality of ports extending from the chamber into the header, perforations in the header 17 in alignment with said ports, and means for establishing coal delivery connections from said perforations directly to the ports and out of communication with the header.

14. The combination with a gasifying chamber, of a header for the collection of 15 generated gases from the chamber, a port for delivering gas from the chamber into said header, there being a perforation in the header, and means for establishing a fuel delivery connection from said perforation to 20 said port out of communication with the interior of the header for the purpose of delivering fuel directly from the perforation to the port.

15. The combination with a gasifying chamber, of a header for the collection of generated gases, a port for the delivery of 25 the gases from the chamber to the header, a fuel delivery pipe, and means for establishing connection from said pipe to the port independently of the header.

16. The combination with a gasifying chamber, of a header for the collection of generated gases, a port for the delivery of 30 the gases from the chamber to the header, a pipe for the delivery of fuel, and means for effecting connections from said pipe to the port and for isolating the port from the 35 header.

17. The combination with a gasifying chamber, of a header for generated gases, a

port for delivering the gases from the said chamber to the header, a fuel delivery pipe, and means for simultaneously effecting connection from said pipe to the said chamber 45 and for isolating the port from the header.

18. The combination with gas producing means, and gas collecting means, of a connection from the gas producing means to the gas collecting means, and means for establishing communication from said connection to the atmosphere and for isolating the communication means from the collecting means. 50

19. The combination with gas producing means, and gas collecting means, of a connection from the producing means to the collecting means, and means for simultaneously establishing communication between said connection and the atmosphere, and for isolating the connection from the collecting 55 means.

20. The combination with gas producing means, and gas collecting means, of a connection from the producing means to the collecting means, means for introducing oil or 60 the like into the collecting means, and means for preventing the entrance of said oil or the like into the connection.

21. The combination with gas producing means, and gas collecting means, of a connection from the producing means to the collecting means, means for introducing oil or 65 the like into the collecting means, and means for preventing the entrance of said oil or the like into the connection, while allowing 70 the flow of the oil or the like along the floor of the collecting means. 75

ARTHUR ROBERTS.
